UNITED STATES PATENT OFFICE.

JOHN C. BACKERT, OF BROOKLYN, NEW YORK.

CUTTING-MACHINE.

1,220,390.

Specification of Letters Patent. Patented Mar. 27, 1917.

Application filed July 28, 1916. Serial No. 111,793.

To all whom it may concern:

Be it known that I, JOHN C. BACKERT, a citizen of the United States of America, residing at Brooklyn, Kings county, New York, have invented a new and useful Cutting-Machine, of which the following is a specification.

My invention relates particularly to machines for cutting printers' rules and slugs, 10 and some of the objects of the invention are to provide a simple, powerful mechanism for this purpose which can be readily set for cutting in different lengths or different angles.

Other and more specific objects are to improve the work holding means, to enable the quick raising or lowering of the cutter for cutting through or "undercutting" the work, and to provide an adjustable driving connection 20 between the motor and the cutter.

In the accomplishment of the foregoing and other objects, I mount the work holding gage on a slide which is movable toward and away from the back rest for the work, said 25 slide being freely movable to carry the gage up into engagement with the work and being then operated by a screw or cam to force the gage into gripping relation with the work.

The work holding gage is preferably 30 pivotally mounted on the slide, and means are provided for preventing it coming into engagement with the cutter.

The back against which the work rests is, according to this invention, provided with 35 a dependent pivot stud offset forwardly from the end thereof and pivotally engaged in a socket formed in the work supporting table.

The cutter is mounted on a bracket which 40 can be readily raised and lowered with respect to the table, and which forms, in the normal position of the parts, a closure to an opening formed in the top of a table.

The cutter is preferably driven by a motor 45 which is connected to the cutter brackets so as to move therewith and maintain the driving connections in proper relation in all positions of the cutter.

Various other features and details of construction will appear as the specification 50 proceeds, attention being directed to the accompanying drawings wherein I have illustrated the invention embodied in a practical and preferred form.

In said drawings:

Figure 1 is a side elevation of a machine

constructed in accordance with and embodying the invention.

Fig. 2 is a top plan view of the same, showing in dotted lines the back swung 60 around for cutting at an angle.

Fig. 3 is a detached bottom plan view of the work supporting table showing the gage adjusting mechanism.

Fig. 4 is a cross sectional view of the same 65 taken substantially on the plane of the line 4-4, Fig. 3.

Fig. 5 is a fragmentary vertical sectional view of the cutter supporting bracket and associated parts taken substantially on the 70 plane of the line 5-5, of Fig. 2.

Fig. 6 is a horizontal sectional view of the machine taken substantially on the plane of the line 6-6 of Fig. 1.

Fig. 7 is a detached perspective view of a 75 "straddle clamp" for holding the work.

Fig. 8 is a broken sectional view taken substantially on the plane of the line 8-8, Fig. 2.

Fig. 9 is a perspective view of certain 80 parts.

The frame or base of the machine is made up, in the present illustration, of a pedestal 10, supporting a table 11. Mounted in suitable guides on the table 11 is a movable 85 work supporting table 12, said table adapted to carry the work up to the cutter and being provided with a transversely extending back 13 against which the work 14 rests.

15 designates the cutter, the same preferably being in the nature of a milling cutter, such as that disclosed in my Patent #1,136,085, and constructed to trim the severed ends of the material and thus leave finished surfaces at the ends of the pieces 95 cut apart.

This cutter is mounted on a shaft 16 journaled in a bracket 17, said bracket being pivotally supported in the present instance at 18 at a point beneath and to one side of an 100 opening 19 in the table top, and being provided with a flat upper surface 20 providing in the normal position of the parts (Figs. 2 and 5) a closure to said opening in the table top.

A handle 21 is shown provided for swinging the cutter bracket on its pivotal support for the purpose of raising and lowering the cutter, said handle having in this case, a segmental slot 22 therein through which passes 110 the shank of a hand operated clamping bolt 23. This provides a ready means for hold-

ing the cutter locked at any desired elevation.

The cutter is driven, in the machine illustrated, by a motor 24, the driving connection 5 from said motor to the cutter being here shown as a pulley 25 on the motor shaft, over which passes a belt 26 to a pulley 27 on the cutter shaft.

This driving connection is maintained at 10 the proper tension and the motor is caused to follow the movements of the cutter by supporting the motor on an arm 28 which is pivoted on the machine frame at 29, and connecting this motor supporting arm with 15 the cutter supporting bracket by means of a link connection 30. This link connection is shown as a guard surrounding and protecting the belt and pulley, and is shown connected at the upper end with the cutter 20 bracket by means of a yoke 31 and connected at its lower end with the motor support by a pivot bolt 32. Adjustment for taking up the slack of the belt is provided by extending said pivot bolt through a slot 33 in a 25 lug 34 on the motor supporting arm, said bolt being clamped at different points in said slot by a clamping nut 35 and having a freely pivoting engagement at its outer end in the belt incasing link, disengagement 30 of said link from the pivot bolt being prevented by the nut 36.

From this, it will be seen that the cutter may be readily raised or lowered, and that the motor will freely follow the adjustments 35 of the cutter, proper driving connections being maintained at all times.

The work on the table 12, which is relatively movable with respect to the cutter, is held against the back 13 by a gage 37, said 40 gage being shown in Figs. 1 and 2 as a relatively thin member disposed parallel to the cutting plane, which is indicated by the line 38 at the edge of the movable table, and pivotally supported at its end farthest from 45 the back by a pivot stud 39 disposed at a right angle to the cutting plane and rotatably engaged in a bearing socket 40 mounted on the slide 41. This gage supporting 50 slide 41 is engaged in a guide-way 42 in the top of the movable table, said slide being ordinarily free to permit of the gage being brought freely up against the work.

After the preliminary or rough adjustment of the gage with respect to the work 55 against the back rest, the holding gage is set up into clamping engagement with the work by means consisting in the present disclosure of a cam 43 carried by a control rod 44 and engaging a dog holding member 45 sleeved on said rod, said holding member having pivoted thereon at 46 a dog 60 47 adapted for engagement with a series of ratchet teeth 48 on the underside of the slide. The dog holder 45 is held in proper 65 engagement with the cam by means such

as the spring 49 and the spring 50 is shown provided for thrusting the dog outward into engagement with the ratchet teeth. The slide may be provided with a handle 51 for operating the same.

In operation: The work is placed up against the back 13 and the slide is then shifted to bring the end of the work holding gage into engagement with the work. The control rod 44 is then turned, as by 75 means of the hand wheels 52 on the ends of the same, the rotation thus imparted to the cam 43 serving to shift the dog carrier longitudinally or parallel with the slide. As soon as the dog moves far enough forward 80 for the lug 53 thereon to become disengaged from the stop 54, the spring 50 thrusts the dog into engagement with the ratchet teeth and thereafter the movement of the cam is effective in shifting the slide, and thus carrying the work holding gage into clamping engagement with the work. The stop 54 thus, when the dog carrier is in the retracted position, serves to trip the dog 85 from engagement with the ratchet, so that 90 in this retracted position the gage carrying slide can be freely moved back and forth, and even when the parts have been left in the position indicated in Fig. 3, the slide 95 can be freely advanced toward the work, because the spring pressed dog will yield as the ratchet travels forwardly.

An end gage 55 is usually provided for gaging the length of the stock, said gage being slidably mounted on the back 13.

In order that the work may be supported at both sides of the cutter, an extension back 56 is preferably carried by the movable table, said back being disposed in line with the back 13 and a break or interruption 57 105 being provided between these two back members in line with the cutter. An end gage 58 is usually provided on the extension back 56 so that both ends of the work can be accurately gaged and held.

In Fig. 7 I have illustrated a special form of holding gage adapted to clamp the work at both sides of the break in the back rest, said gage having holding portions 59 and 60 connected in spaced relation by an arch 115 61 so as to engage the stock at opposite sides of the cutting plane and straddle the cutter as the work table is advanced.

To insure the proper lateral positioning of this straddle gage with respect to the cutter, positioning means are preferably provided such as a dependent lug 62 on the gage working in a slot 63 in the table top. This prevents the work holding gage getting out of alignment with respect to the 125 cutter and at the same time allows for adjustment of the gage with respect to the back.

The different kinds of work holding gages are made interchangeable by provid-

ing them each with a pivot stud 39 which can be slipped endwise into the bearing 40 on the slide 41, and in order to temporarily lock the gage in said socket, I have shown 5 holding means in the form of a lug 64 on each pivot stud 39, which, when the gage is turned up into an inoperative position, comes into the plane of a slot 65 in the bearing 40, permitting the pivot stud being 10 shifted endwise until the lug passes out of the opposite end of the bearing whereupon the gage may be dropped down into operative position. This lug 64 is so disposed as to limit the movement of the holding gage 15 toward the cutter and prevent the gage being moved over far enough to strike the cutter. The gage, may, however, be freely moved in the opposite direction or away from the cutting plane, as will be evident in 20 Fig. 2.

The motor is by preference, electrically operated, in which case the controlling switch 66 for the same may be conveniently located at the front of the machine beneath 25 the stationary table top. The motor is usually located at the rear side of the machine beneath the projecting portion of the stationary table top. This arrangement provides a compact structure taking up but 30 very little room.

The pedestal 10 in the machine is usually of hollow construction and a chip receptacle 67 may be removably mounted in said hollow pedestal, said receptacle being supported by means of hooked lugs 68 bearing 35 on supporting ledges 69 on the inside of the frame, and being withdrawable through the open side 70 of the pedestal.

The gages described are readily adjustable for various lengths of stock, and as an additional feature, the back 13 is preferably pivotally mounted so that it may be swung around into the desired position indicated 40 in Fig. 2 for mitering purposes. This is accomplished in the illustration by providing said back with a dependent pivot lug 71 offset forwardly from the end of the back and engaging in a socket 72 in the movable table. This hinge mounting is entirely out of the 45 way so as not to interfere with the placing of the work, and allows for the easy setting of the back to the requisite angle, said back being held at the proper point as by means 50 of a holding pin 73 engaging in properly positioned openings 74 in the movable table top.

The machine of my invention will be seen to be of simple, sturdy construction, and it 55 will be evident that it is quickly adaptable to meet the various uses for which said machines are intended.

What I claim is:

1. In a machine of the character set forth, 60 the combination of a cutter and a work supporting table relatively movable with re-

spect to each other, said table having a socket in the top thereof at one side of the cutting plane of the cutter and a back rest for the work having a supporting face for engagement with the work provided with 70 measurement indications and having a dependent pivot stud offset forwardly from the plane of the working face of said back rest and pivotally engaged in the socket in the table. 75

2. In a machine of the character set forth, the combination of a relatively movable cutter and work supporting table, said table having a groove in the top thereof parallel to the cutting plane of the cutter, a back 80 rest for the work on the table, a slide on the table movable toward and away from the back rest and a holding gage pivoted on said slide and provided with a lug adapted to drop into the groove in the table top 85 whereby in the sliding movements of said slide the pivoted holding gage will be guided by engagement in the groove aforesaid.

3. In a machine of the character set forth, the combination of a relatively movable cutter, 90 and work supporting table, a back rest for the work on said table, a slide mounted on the table and movable thereon toward and away from said back rest and a work holding member pivoted on said slide at a 95 right angle to the cutting plane of the cutter.

4. In a machine of the character set forth, the combination of a relatively movable cutter and work supporting table, a back rest 100 for the work on said table, a slide mounted on the table and movable thereon toward and away from said back rest and provided with a socket disposed at a right angle to the cutting plane of the cutter and a work holding gage disposed parallel to the cutting plane 105 provided with a supporting stud pivotally engaged in said socket.

5. In a machine of the character set forth, the combination of a relatively movable cutter and work supporting table, a back rest 110 for the work on said table, a slide mounted on the table and movable thereon toward and away from said back rest and provided with a socket disposed at a right angle to the cutting plane of the cutter, a work holding gage disposed parallel to the cutting plane 115 and provided with a supporting stud pivotally engaged in said socket and a stop limiting the movement of said holding gage 120 toward the cutting plane.

6. In a machine of the character set forth, the combination of a relatively movable cutter and work supporting table, a back rest for the work on said table, a slide mounted 125 on the table and movable thereon toward and away from said back rest and provided with a socket disposed at a right angle to the cutting plane of the cutter, a work holding gage disposed parallel to the cutting plane 130

provided with a supporting stud pivotally engaged in said socket, said socket having a slot in one side thereof and a pin on the pivot of the work holding gage engageable in said slot when the pivot stud is inserted endwise into the socket.

7. In a machine of the character set forth, relatively movable cutter and table elements, a supporting sleeve on said table, a stud pivotally engaged in said sleeve and longitudinally slidably therein, a work holding gage at the end of said stud nearest the cutter and an outstanding lug on the opposite end of the pivot stud engaging the end of the supporting sleeve to limit the movement of the gage toward the cutter and said supporting sleeve having a longitudinal slot therein for the passage of said lug but offset from the plane of the lug when the gage is in operative position.

8. In a machine of the character set forth, the combination of a cutter, a table slidably mounted at one side of the cutting plane of said cutter, a back rest for the work carried by said table and provided with a break therein in line with the cutting plane, a gage mounted on the table in front of the back rest and provided with work engaging portions disposed on opposite sides of the cutting plane for engaging the work bearing against the back rest at opposite sides of the break therein, the table having a groove therein parallel with the cutting plane and said gage having a lug engaging in said groove for holding said gage against lateral shifting with respect to the cutter.

9. In a machine of the character set forth, the combination of a work supporting table, a back on said table, a slide movable on the table toward and away from said back, a work holding gage carried by said slide for coöperation with said back, a series of ratchet teeth on said slide, a dog for engagement with said ratchet teeth and means for simultaneously shifting said dog toward the ratchet teeth and in a plane parallel to the plane of movement of the slide.

10. In a machine of the character set forth, the combination of a work supporting table, a back rest on said table, a slide movable on the table toward and away from said back rest, a work holding gage carried by said slide for coöperation with said back rest, a series of ratchet teeth on said slide, a dog engageable with the ratchet teeth and movable in a plane parallel to the movement of the slide, a cam for forcing said dog forwardly in such plane of movement and means for tripping the dog from engagement with the ratchet teeth.

11. In a machine of the character set forth, a work supporting table, a back on said table, a slide on the table, a work holding gage carried by said slide for coöperation with said back, a series of ratchet teeth on said slide,

a rotatable controlling rod, a cam on said rod having relatively high and low points, a dog holder sleeved on said rod, a spring holding said dog holder engaged with the cam, a dog pivoted on said holder, a spring for thrusting said dog toward the ratchet teeth and a stop for lifting the dog out of engagement with the ratchet teeth.

12. In a machine of the character set forth, a work supporting table, a gage support slidably mounted on said table, a rotatable control rod mounted on the table parallel to the slide, a cam fixed on said rod, a dog holder bearing on said cam and movable in a plane parallel to the movement of the slide, a dog pivoted on said holder for engagement with the ratchet teeth and a stop for shifting said dog out of engagement with said ratchet teeth.

13. In a machine of the character set forth, a table having an opening therein, a bracket closing the opening in the table, pivoted below the table adjacent one edge of the opening therein and provided with a flat upper surface to form a continuation of the table top, means for shifting said bracket on its pivot to carry the same into planes above and below the table top and a cutter shaft journaled in said bracket and movable therewith.

14. In a machine of the character set forth, a table having an opening therein, a bracket closing the opening in the table, pivoted below the table adjacent one edge of the opening therein and provided with a flat upper surface to form a continuation of the table top, means for shifting said bracket on its pivot to carry the same into planes above and below the table top, a cutter shaft journaled in said bracket and movable therewith, a pivotally mounted motor support, a link connection between said motor support and pivoted bracket, a motor on the motor support and driving connections from said motor to the cutter shaft.

15. In a machine of the character set forth, a table having an opening therein, a bracket closing the opening in the table pivoted below the table adjacent one edge of the opening therein and provided with a flat upper surface to form a continuation of the table top, a handle connected to said bracket and provided with a segmental slot therein, a clamp working in said segmental slot and a cutter shaft journaled in the bracket and movable therewith.

16. In a machine of the character set forth, a pivoted motor support, a motor mounted thereon, a pivotally mounted swinging bracket, a cutter shaft journaled in said bracket, a link connection between said motor support and cutter shaft and driving connections from the motor on the motor support to the cutter shaft mounted in the movable bracket.

17. In a machine of the character set forth, a pivoted motor support, a motor mounted thereon, a pivotally mounted swinging bracket, a cutter shaft journaled in said bracket, a link connection between said motor support and cutter shaft, belt connections from the motor to the cutter shaft and means for regulating the link connection between the motor support and cutter shaft bracket to vary the tension on the belt connections. 30
- 5 18. In a machine of the character set forth, a pivotally supported bracket, means for raising or lowering said bracket, a cutter shaft journaled in said bracket, a motor support suspended from said pivoted bracket, a motor carried on said motor support and driving connections from said motor to the cutter shaft. 35
- 10 19. In a machine of the character set forth, the combination of a work supporting table, a back rest on said table, a slide movable on the table toward and away from said back rest and pawl and ratchet connections between said table and slide including a ratchet on one of said members, a dog on the other of said members, and means for engaging the dog and ratchet and for im- 40
- 20 parting a movement longitudinal of the slide. 45
- 25 20. In a machine of the character set forth, the combination of a work supporting table, a back rest on said table, a slide movable on the table toward and away from said back rest, pawl and ratchet connections between said table and slide including a ratchet on one of said members and a dog on the other of said members, means for engaging the dog and ratchet and for imparting a movement longitudinal of the slide and means for tripping the dog and ratchet from engagement with each other. 50
- 25 21. In a machine of the character set forth, the combination of a relatively movable cutter and work supporting table, a back rest on the table, a slide on the table movable in a plane parallel to the cutting plane of the cutter and a work holding gage pivoted at one end to the slide and having at its opposite end substantially parallel portions adapted to engage at their ends the work resting against the back rest and arranged to straddle the cutter in the relative movements of the work supporting table and cutter. 55

JOHN C. BACKERT.
